ELECTRIC METER

David L. Swindler, Bedford, and Robert M. Schramm,
Maple Heights, Ohio, assignors to Square D Company,
Park Ridge, Ill., a corporation of Michigan

Filed Mar. 25, 1964, Ser. No. 79,195

Term of patent 14 years

(Cl. D26—1)

FIG. 1.

FIG. 2

FIG. 3 FIG. 4

FIG. 1 is a perspective view of an electric meter showing our new design;

FIG. 2 is a reduced scale front elevational view thereof;

FIG. 3 is a reduced scale right side elevational view thereof;

FIG. 4 is a cross sectional view taken on the line 4—4 of FIG. 2.

The dominant features of our design reside in the full line portion of the drawing.

We claim:

The ornamental design for an electric meter, as shown and described.
